[57] CLAIM

The ornamental design for a rolled material dispenser, as shown and described.

DESCRIPTION

FIG. 1 is a perspective view of a rolled material dispenser showing our new design;

FIG. 2 is a front elevational view thereof, the rear being identical in appearance to that shown; and,

FIG. 3 is a side elevational view thereof, the opposite side being identical to that shown. The broken-line illustration of the rolled material is for illustrative purposes only and forms no part of the claimed design.

FIG. 1

FIG. 2

FIG. 3
